Marie A. Dins.

Attorney

UNITED STATES PATENT OFFICE.

ARTHUR ROBERTS, OF BOGUE, KANSAS.

END GATE.

Application filed January 3, 1925. Serial No. 342.

To all whom it may concern:

Be it known that I, ARTHUR ROBERTS, a citizen of the United States, residing at Bogue, in the county of Graham and State 5 of Kansas, have invented certain new and useful Improvements in an End Gate, of which the following is a specification.

This invention relates to improvements in end gates and more particularly to an 10 improvement over Patent No. 864,692, granted to me August 27, 1907.

One of the important objects of the present invention is to provide an end gate which is adapted to be used in conjunction 15 with wagon or truck bodies, means being provided whereby the end gate may be swung outwardly to provide a scoop board, the end gate being further adapted for vertical slidable movement when the same is 20 to be removed.

A further object of the invention is to provide an end gate of the above mentioned character, wherein means is provided for locking the same in a vertical position 25 against accidental displacement from the wagon body, thus preventing the contents from being spilled or being lost through leakage.

A further object of the invention is to 30 provide an end gate of the above mentioned character, which is simple in construction, inexpensive, strong and durable and furthermore adapted for the purposes for which it is designated.

Other objects and advantages of this invention will become apparent during the course of the following description.

In the accompanying drawing forming a 40 part of this specification and in which like numerals designate like parts throughout the same:

Figure 1 is a perspective view of the end gate.

Figure 2 is a top plan view illustrating 45 more clearly the locking means.

Figure 3 is a sectional view taken approximately on line 3—3 of Figure 2, looking in the direction of the arrow.

Figure 4 is a section taken on line 4—4 50 of Figure 2.

Figure 5 is a detail perspective view of one of the locking bolts and the actuating handle associated therewith, and

Figure 6 is a detail perspective view of a modified form of end gate. 55

In the drawings, wherein for the purpose of illustration is shown the preferred embodiment of my invention, the numeral 1 designates generally a portion of a wagon body of any conventional construction, the 60 sides thereof being indicated at 2 and 3 respectively. A pair of sheet metal plates 4 and 5 are disposed vertically against the inner faces of the sides of the wagon body adjacent the rear end thereof and the upper 65 and lower ends of each of the plates extend around the upper and lower edges of the sides of the wagon body and are secured to the outer faces thereof as is clearly illustrated in Figure 1 of the drawing. The inner edges of the plates are provided with the inwardly extending flanges 6 and 7 respectively, and the same extend from the top of the sides of the wagon body to the bottom thereof. Each of the flanges is provided with the elongated openings or slots 8 and the purpose thereof will be more fully described. 70

The lower ends of the flanges are disposed rearwardly as illustrated at 9 and 80 each of the rearwardly extending portions is provided with an opening 10 which communicates with the cut out portion 11 formed in the bottom 12 of the wagon body at the rear end thereof in the manner as 85 more clearly illustrated in Figure 4.

The end gate is designated generally by the numeral 13. A pair of strap irons or the like shown at 14 are secured on the outer face of the end gate 13 adjacent the 90 respective side edges thereof, curved fingers such as are shown at 15 extend from the lower ends of the strap irons and are adapted to extend through the openings 10 provided in the rearward extension 9 formed 95 on the lower ends of the aforementioned flanges and are disposed within the cut out portions 11 whereby the end gate is hingedly supported at its lower end on the bottom of the wagon body and furthermore the construction of a hinge of the above mentioned character, permits the end gate to be readily removed from the bottom of the wagon body to permit the upward sliding movement of the end gate. 100

A pair of substantially triangular shaped 105

metallic plates 16 and 17 respectively are provided at their outer edges with the flanges 18 and 19 respectively, the latter being secured to the inner side of the end gate 13 adjacent the side edges thereof as is clearly illustrated in the drawings. Outwardly extending flanges 20 and 21 are formed on the lower edges of the plates 16 and 17 and the same cooperate with the flanges 6 and 7 in the manner to be presently described.

The provision of the triangular shaped plates 16 and 17 enables the end gate to be used as a scoop board when the same is swung outwardly from the rear end of the wagon body, the flanges 20 and 21 engaging the flanges 6 and 7 respectively for limiting the outward and downward swinging movement of the end gate. As this construction is more fully covered in my prior patent and as the same forms no important part of the present invention, a further detailed description thereof is not thought necessary.

The locking means associated with the end gate whereby the same will be held in a vertical position between the sides of the wagon body comprises a plurality of bolts shown at 22, the same extending through the strap iron on the outer side of the end gate 13 and through the flanges 18 and 19 and further through the elongated openings or slots 8 provided therefor in the flanges 6 and 7. The inner ends of the bolts have formed thereon the heads 23 which are of such construction as to permit the same to be readily insertable or removable through the openings 8 in the aforementioned flanges. The heads 23 are adapted for engagement with the inner sides of the flanges 6 and 7 when the bolts are in a locked position in the manner clearly illustrated in Figure 3. For the purpose of actuating the bolts so that the end gate may be unlocked, handles such as are shown at 24 are secured on the outer ends of the bolts, the nuts 25 holding the handles against displacement from the bolts. It is obvious that when the handles 24 are turned so that the same are disposed in a horizontal position, the head 23 will be brought into alignment with the elongated slots or openings 8 and the end gate 13 may then be swung outwardly from the wagon body or may further be detached from the extensions 9 whereby the gate will be permitted to slide vertically between the sides of the wagon body and enable the end gate to be entirely removed from the wagon body. The end gate 13 is provided with a hinged lower section 26, the same being adapted to swing upwardly when the end gate is used in connection with a wagon body in which is contained grain or the like. Any suitable means such as is shown at 27 is associated with the hinged section 26 for locking the same in a closed position so that

the leakage of the grain from the wagon body will be prevented.

In Figure 6 of the drawing, a modification of the end gate is shown wherein the same includes the upper and lower sections 28 and 29 respectively. A protector strip 30 is secured to the upper section 28 adjacent the lower edge thereof and extends over the adjacent edges of the sections. As the end gate shown in Figure 6 is provided with the locking means, the construction of which has already heretofore been more fully described, it is not thought necessary to further go into detail relative to the same.

The provision of an end gate of the above mentioned character, obviates the necessity of having to employ the usual fastening rods and the like employed in connection with the end gates now universally in use. Furthermore, the simplicity in which my device is constructed enables the parts to be readily assembled or disassembled without the loss of any considerable length of time or labor.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. In combination with a wagon body, a pair of opposed angle iron members secured on the inner sides of the wagon body adjacent the rear end thereof, an end gate adapted to be detachably and hingedly supported at its lower end to the bottom of the wagon body, means for securing the end gate in a vertical position, said means comprising bolts extending transversely through the end gate and through registering elongated openings provided in the angle iron members, heads on the inner ends of the bolts adapted for engagement with the inner faces of the angle iron members, and handles on the outer ends of said bolts for rotating the same to bring the heads into alignment with the openings whereby the gate is adapted for swinging or vertical sliding movement.

2. In combination with a wagon body, a pair of plates secured on the inner opposed sides of the sides of the wagon body adjacent the rear end thereof and extending vertically from the top to the bottom of the wagon body, inwardly extending flanges formed on the inner ends of said plates, said flanges being provided with a series of elongated openings, an end gate adapted to be detachably and hingedly supported at its lower end to the bottom of the wagon body, a series of bolts extending transversely

through the end gate adjacent the sides thereof, heads formed on the inner ends of said bolts adapted to extend through the elongated openings in the aforementioned flanges, said heads adapted to engage the inner sides of the flanges when in one position whereby the end gate is secured in the locked position on the wagon body, said

heads adapted to be moved in alignment with the openings to permit the removal of 10 the end gate from its locked position, and handles on the other ends of the bolts for actuating the same.

In testimony whereof I affix my signature.

ARTHUR ROBERTS.
